UNITED STATES PATENT OFFICE.

WILLIAM R. HILL, OF ROCHESTER, NEW YORK, ASSIGNOR TO SARGENT & GREENLEAF, INC., OF ROCHESTER, NEW YORK, A CORPORATION OF NEW YORK.

LOCK MECHANISM.

Application filed April 10, 1925. Serial No. 22,092.

The present invention relates to a lock mechanism and has for its object to provide improvements in locks, particularly of the combination type such as are used on safes, vaults and the like.

A further object of the invention is to provide an improved lock operating or control mechanism embodying a simple, economical and reliable form of construction capable of being quickly and easily assembled and applied to a door or closure and being of a nature whereby the tumbler mechanism will be rendered inoperative should the exterior control means be broken off or the operating rod driven in.

A further object of the invention is to provide a combination lock and control means therefor embodying one or more units which can be separately constructed and subsequently connected with a door or closure in a comparatively short time and which will be readily detachable and adapted for application to doors or closures of different sizes or thicknesses.

To these and other ends the invention resides in certain improvements and combinations of parts, all as will be hereinafter more fully described, the novel features being pointed out in the claims at the end of the specification.

In the drawings:—

Figure 1 is a plan view partly in section of a lock mechanism embodying the invention;

Figure 2 is a front elevation of the lock mechanism shown in Figure 1;

Figure 3 is a central sectional view on an enlarged scale with certain parts in elevation;

Figure 4 is a similar view with additional parts shown in section;

Figure 5 is a sectional view taken on line 5—5 of Figure 4;

Figure 6 is a sectional view taken on line 6—6 of Figure 4;

Figure 7 is a sectional view on line 7—7 of Figure 4; and

Figure 8 is a detailed view in elevation of one of the lock control members shown in section in Figure 4.

Similar reference numerals throughout the several views indicate the same parts.

In the embodiment of the invention illustrated in the drawings I have shown a door

or closure 10 which may be that of a safe 55 or vault having any suitable lock or locking mechanism on the inner face thereof, preferably a permutation or combination lock of any well known design, including a housing or casing 11 suitably connected with the closure by means accessible only from the inside thereof. The closure is provided with an opening 12 of relatively large size for accommodating the connecting means between the lock proper and the control 60 means therefor on the outer face of the closure. The connecting means in the present instance comprises a tubular member 13, connected with the lock housing or casing 11 in any suitable manner, preferably by being sleeved upon an extension 14 thereof as indicated by dotted lines in Figure 1 and secured thereto by suitable means such as a pin 15, or by driving inwardly a portion of the metal of the tubular member into 65 a recess formed in the extension 14. The lock and tubular extension constitute a 70 unitary construction which can be applied to the closure as such with suitable fastening means provided for the lock, not shown. The outer end of the tubular member is threaded and also recessed or slotted as indicated at 16 and forms a support for the dial ring or base plate 17, the latter being 75 slidably disposed upon the tubular member 80 and having tongues or projections 18 extending into the slots 16 as shown in Figures 4 and 6. Inner and outer nuts 19 and 20, respectively, are threaded upon the tubular member to permit the dial ring or base 85 plate to be adjustably positioned thereon, 90 whereby to take care of any variation that may occur in the thickness of the doors or closures 10, the base plate being clamped upon the outer face of the closure by tightening the nut 20. The construction above 95 described can be assembled and applied to the closure before applying the lock control or operating mechanism which will now be described.

The lock operating or control means embodies a rod or bolt 21 disposed within the tubular member 13 and projecting into the lock housing and having thereon or connected therewith an operating member 22 105 of any suitable design for actuating a series of tumblers or other lock controlling parts not shown. The outer end of the rod 21 is

preferably threaded to receive a grooved head or actuating member 23 as best shown in Figures 4 and 8, said member being securely held against turning upon the rod 5 by a pin 24 as shown in Figures 4 and 6. The head 23 is provided with a reduced extension 25 having a bearing within the outer end of the tubular member 13 and is also provided with a somewhat larger threaded portion 26, the inner end of which has a bearing on the outer end of the tubular member, as shown in Figure 4. The head is further provided with oppositely disposed grooves or recesses 27 for a purpose which 10 will hereinafter appear.

A dial plate 28 is provided having the usual graduations and characters for co-operation with an indicating mark 29 on the dial base plate, whereby anyone entrusted 20 with the combination may open the safe or vault when desired. The base plate 17 is preferably dished or recessed as indicated at 30 to receive the dial plate, the latter being slidably disposed on the portion 26 25 of the head 23 and having tongues or projections 31 extending into the grooves 27 so that rotation of the head will effect rotation of the dial. The dial is preferably provided with a finish plate 32 clamped against 30 a shoulder portion 33 of the head by the dial plate, upon the tightening of the nut 34 screwed upon the threaded portion 26 of the head. The head also forms a support for a knob or handle by which the rod 21 35 is rotated, the knob preferably embodying a ring 35 of any suitable material surrounding the head and clamped upon the finish plate 32 by an outer ring 36 which may be constructed of hard rubber or any other 40 suitable material and which is preferably fluted or grooved as shown at 37 to facilitate gripping and turning of the knob by the operator. The ring 36 is provided with inwardly disposed ribs 38 projecting into the 45 grooves 27 of the head to effect rotation of the rod. The rings 35 and 36 are clamped in position by a plate 39 having a threaded member 40 screwed into the head 23 as shown in Figure 4. The member 40 is preferably slotted at 41 to receive a screw driver 50 by which the plate 39 may be tightly clamped upon the ring 36 before the rod 21 is screwed within the head, although said plate may be screwed into position upon or 55 removed from the head by an exterior operation if desired. Rotation of the lock control rod 21 is of course effected by turning the knob or handle in the desired direction, it being remembered that the inner end 60 of the head is rotatably disposed within or upon the outer end of the tubular member 13 as above stated.

The rod 21, head 23, dial plate 28 and knob form a complete unit which is constructed and applied as such by inserting

the rod through the tubular member into the lock, after which the tumbler control member 22 and such other lock control parts as may be desired are inserted upon the rod and secured in any suitable manner, before 70 the cover plate 43 is applied to the lock casting, as by a key 42 driven into a keyway formed in the end of the rod. Any suitable form of latch or lock bolt not shown may be employed in connection with the lock. 75

From the construction shown it will be apparent that if it is attempted to open the safe by breaking off the knob and driving in the control rod, operation of the tumblers cannot be effected since the rod and parts thereon form the only control or operating means for the tumblers. 80

While the construction shown in the drawings affords a simple and practical embodiment of the invention it will be understood that the different forms of construction and arrangements of parts shown may be modified to a certain extent without departing from the scope of the invention as covered by the claims. 90

I claim as my invention:

1. In lock mechanism, the combination with a closure and a lock thereon, of a dial base plate disposed upon the outer face of the closure, a tube projecting from the lock through the closure and base plate and permitting adjustment of the latter thereon, a dial plate, operating means therefor rotatable upon said tube and lock controlling means connected with said dial operating means and projecting through said tube. 100

2. In lock mechanism, the combination with a closure and a lock thereon, of a dial base plate disposed on the outer face of the closure, a dial plate, a tubular connection between the lock and base plate adapted to project through the latter and permitting it to be adjusted longitudinally thereon, means for locking the base plate upon the tubular connection, operating means for the dial plate including a member having a portion projecting into said tubular connection and a shoulder portion abutting the outer end thereof, and lock controlling means connected with said member and projecting through the tubular connection. 110

3. In lock mechanism, the combination with a closure and a lock thereon, of a dial base plate upon the outer face of the closure, a dial plate adjacent the base plate, a tubular connection between the lock and base plate, operating means for the dial plate including inner and outer parts slidably disposed one upon another and having retaining means therefor, and a lock control member connected with one of said parts and extended through said tubular member to the lock. 120

4. In lock mechanism, the combination with a closure and a lock thereon, of a dial

base plate upon the outer face of the closure, connecting means between the base plate and the lock, an operating connection for the lock projecting through said connecting means, a head secured to the operating connection and rotatable upon said connecting means, a dial plate slidable upon the head and held against rotation thereby, a knob carried by the head, and means adjustable upon the head adapted to clamp the dial plate upon the knob.

5. In a lock mechanism, the combination with a closure and a lock on one side thereof having a tubular member projecting through the closure, of a dial base plate slidable to different positions of adjustment upon the outer end of the tubular member and adapted to be held against rotation thereby, means adjustably connecting the base plate with 15 said tubular member, a dial plate adjacent the base plate and a control member for the lock projecting through the tubular member and connected with the dial plate.

6. In lock mechanism, the combination with a closure and a lock on one side thereof, of a tubular member projecting from the lock through the closure, a dial base plate slidable to different positions of adjustment upon the outer end of the tubular member 20 and adapted to be held against rotation thereby, means adjustably connecting the base plate to said tubular member, a lock operating connection disposed within said tubular member, a dial plate slidably disposed upon said operating connection and means adapted to secure the dial plate thereon.

7. In lock mechanism, the combination with a closure and a lock on one side thereof, of a tubular member projecting from the lock through the closure and having a groove formed in its outer end, a dial base plate upon the outer face of the closure slidably disposed upon said tubular member and having a portion projecting into the groove thereof to prevent turning of the base plate, means for preventing longitudinal movement of the base plate upon said tubular member, an operating connection for the lock disposed within the tubular member, and 45 a dial plate carried by said operating connection adjacent the base plate.

8. In lock mechanism, the combination with a closure and a lock on one side thereof, of a tubular member projecting from the lock through the closure and having a recess formed in its outer end, a dial base plate on the outer face of the closure slidably disposed upon said tubular member and having a portion projecting into said recess to prevent turning of the base plate upon the tubular member, means for preventing longitudinal movement of the base plate upon said tubular member, an operating connection for the lock projecting within the tubular member, a dial plate slidably disposed

upon said connection, and operating means for the dial plate adapted to secure it upon said operating connection.

9. In lock mechanism, the combination with a closure and a lock on one side thereof, of a dial base plate on the opposite side of the closure, connecting means between the lock and base plate, operating means for the lock projecting through said connecting means and including a recessed member adjacent said base plate, a dial plate slidably mounted upon the recessed member and having a portion projecting into the recess thereof to afford means for turning the dial plate, and means on said recessed member for holding the dial plate against longitudinal movement thereon.

10. In lock mechanism, the combination with a closure and a lock on one side thereof, of a dial base plate on the opposite side of the closure, a tubular member connecting the lock and base plate and having threads at its outer end and also provided with a recess into which projects a portion of the base plate, nuts screwed upon said threaded portion on opposite sides of the base plate to adjustably position the latter, a dial plate adjacent the base plate, and lock control means connected with the dial plate and projecting through said tubular member.

11. In lock mechanism, the combination with a closure and a lock on one side thereof, of a dial base plate on the opposite side of the closure, connecting means between the lock and base plate, a grooved member engaging said connecting means and operatively connected with the lock therethrough, a dial plate slidably disposed upon said grooved member and having a portion projecting into the groove thereof, an adjustable member upon the grooved member for limiting the movement of the dial plate relative to the base plate, and a knob secured upon the grooved member and adapted to clamp the dial plate upon said adjustable member.

12. In lock mechanism, the combination with a closure having an opening therethrough and a lock disposed on the inner face of the closure and having a tubular member projecting through said opening, of a dial base plate slidable upon said member on the outer face of the closure and held against turning thereby, and a detachable control unit for the lock embodying an operating member projecting through said tubular member into the lock and a dial plate and knob upon the operating member.

13. In a lock mechanism, the combination with a closure having an opening therethrough and a unit upon the closure embodying a lock and a tubular securing member thereon projecting through the opening, a dial base plate slidably upon and held against turning on the tubular member on the outer face of the closure, and a detach-

able control unit for the lock comprising an operating member, a head thereon rotatably disposed upon the tubular member, a dial plate upon the head, and a knob upon the head for securing the dial plate thereon.

14. A device of the class described, comprising a tubular support adapted for connection with a lock, a dial base plate slidably adjustable upon the outer end of the support, means for locking the plate in different positions of adjustment, a lock control device disposed within the tubular support, and a dial plate adjacent the base carried by the said control device.

15. A device of the class described, comprising a tubular support adapted for connection with a lock, a dial base plate slidably upon the outer end of the support and held against turning thereby, means for locking said plate in different positions upon the support, a lock control device disposed within the support, a dial plate disposed upon said control device and a knob upon the control device adapted to secure the dial plate thereon.

16. In combination, a closure having an opening therethrough, a lock fixed on the

inner face of the closure, a member projecting through the opening and having its rear end secured to and held against rotation upon the lock, an element on the outer end of said member adjustable longitudinally thereon for engagement with the outer face of the closure, a rod extending forwardly from the lock through the opening, and an operating device for the rod secured upon its outer end, said lock being secured to the closure in a manner to remain fixed thereon should the operating device be removed and the rod driven in.

17. In combination, a closure having an opening therethrough, a lock fixed on the inner face of the closure, a tube projecting through the opening and having its inner end secured to the lock and held against rotation within the opening, an element adjustably secured on the outer end of said tube for engagement with the outer face of the closure, a rod extending forwardly from the lock through the tube and an operating device for the rod detachably secured on its outer end adjacent said element.

WILLIAM R. HILL.
